(57) **CLAIM**

The ornamental design for a clamping device, as shown and described.

DESCRIPTION

FIG. 1 is a front view of the clamping device;
FIG. 2 is a left side view thereof;
FIG. 3 is a right side view thereof;
FIG. 4 is a rear view thereof;
FIG. 5 is a top view thereof;
FIG. 6 is a bottom view thereof; and,
FIG. 7 is a perspective view thereof.
The broken line showing of parts of the drawings is included for the purpose of illustrating use and environment and forms no part of the claimed design.
